(57) CLAIM

I claim the ornamental design for a golf club head, substantially as shown and described.

DESCRIPTION

FIG. 1 is a front elevational view of my design for a golf club head;

FIG. 2 is a rear elevational view thereof;

FIG. 3 is a top plan view thereof;

FIG. 4 is a bottom plan view thereof;

FIG. 5 is a toe side elevational view thereof;

FIG. 6 is a heel side elevational view thereof;

FIG. 7 is a top perspective view thereof; and,

FIG. 8 is a bottom perspective view thereof.

The broken lines are for illustrative purposes only and formed no part of the claimed design.
